[57] CLAIM

The ornamental design for snow pusher, as shown.

DESCRIPTION

FIG. 1 is a perspective view of a snow pusher showing our new design;

FIG. 2 is a front view thereof;

FIG. 3 is a left side view thereof, the right side view being a mirror image and symmetrical thereto;

FIG. 4 is a back view thereof;

FIG. 5 is a bottom view thereof;

FIG. 6 is a top view thereof;

FIG. 7 is a perspective view of a second embodiment of the design shown in FIG. 1;

FIG. 8 is a front view thereof;

FIG. 9 is a left side view thereof, the right side view being a mirror image and symmetrical thereto;

FIG. 10 is a back view thereof;

FIG. 11 is a bottom view thereof; and,

FIG. 12 is a top view thereof.
